UNITED STATES PATENT OFFICE

ERICH H. LICHTENBERG, OF MILWAUKEE, WISCONSIN, ASSIGNOR TO KOEHRING COMPANY, OF MILWAUKEE, WISCONSIN, A CORPORATION

SKIP HOISTING MECHANISM FOR CONCRETE MIXERS

Application filed September 5, 1929. Serial No. 390,578.

Concrete mixing apparatus of the type now generally known in which a cable operated loading skip for charging the mixing drum is employed, has customarily embodied high superstructure framework, by means of which it has been possible to readily obtain a sufficient elevation of the charging skip by its operating cable to effect the charging of the aggregate materials into the mixing drum.

As these machines have increased in size and height, serious problems of transportation have been encountered. These have been generally met by providing superstructure of a knock-down, detachable or hinged type, necessarily increasing the manufacturing and assembly costs and rendering more and more desirable a low overhead type of construction. Bearing in mind, however,

that the proper elevation of the loading skip must of necessity correspondingly prevail in such low overhead constructions, an engineering problem of no little moment is met with.

It is the primary object of these improvements to provide a special skip hoisting mechanism which obtains the required skip elevation for readily charging the aggregates into the drum, in combination with a low overhead superstructure which eliminates time wasting adjustments or disassembling operations heretofore required to enable the machines to clear low overheads.

Among other objects of my invention may be mentioned the simplification of the cable winding mechanism, its centralization and close association with the power unit, and the provision for variation in the lifting leverage during the elevation of the skip.

Other and further objects and advantages of the invention will be hereinafter set forth and the novel features thereof defined by the appended claims.

In the drawings:

Fig. 1 is a fragmentary side elevation of a mixing machine having my skip hoisting mechanism applied thereto;

Fig. 2 is a front elevation thereof; and

Fig. 3 is a fragmentary diagrammatic view showing more particularly the posi-

tions assumed by the cable in the different positions of the skip.

Like numerals refer to like parts in the several figures of the drawings in which 10 designates a mixing drum mounted upon the supporting frame 11, and 12 the loading skip having the angularly arranged arms 13 pivoted upon the transverse axis 14. This skip is operated by cable means 15, in this instance a double cable, although I desire it to be understood that I do not wish to be restricted to the use of a double cable arrangement. I prefer to use two cables, however, for safety purposes, each of the cables being capable of sustaining the maximum stresses encountered in the operation of the apparatus.

One end of each of the cables is connected to the winding drum 16 mounted at one end of the drum shaft 17 and passes upwardly therefrom over a double sheave 18 mounted at one side and intermediate the length of the upper frame member 19, then forwardly over a wide guide sheave 20 at one end of the frame, downwardly about the skip, then over the companion wide sheave 20' at the other side of the machine, the double sheave 18', and finally back to the winding drum 16' on the other end of the shaft 17. An important feature of this arrangement resides in the positioning of this cable winding unit at a point centrally of the frame and adjacent to its base and the prime mover 21, thereby centralizing the hoisting stresses and eliminating the side or unequalized stresses found in most apparatus of this type.

Power is transmitted to the shaft 17 from the pinion 22 and gear 23 on the shaft 24, through the pinion 25 to the gear 26 on one end of the cross shaft 27, from which the drive is passed through the skip hoist clutch 27' to the pinion 28 on the other end of the shaft 27, and then to the large driving gear 29 on the drum shaft 17.

It will be obvious from the foregoing explanation that during the initial sector of the pivotal swing of the skip, the major component of the lifting force is substantially vertical owing to the position occupied

by the sheaves 20, 20' in relation to the connection of the cable with the skip. After the skip has reached a position corresponding to the full line position shown in Fig. 1, the cable means leaves the sheaves 20, 20', which previously guided the cables and held their side reaches separated to the maximum extent, and the major component of the lifting force then assumes a substantially horizontal direction.

When the cables leave the sheaves 20, 20', there is an advantageous change in the leverage arm and this is of particular importance in view of the greater demand on the power due to the mixing action in the drum.

In Fig. 3 I have shown diagrammatically the position of the cable when the skip is in its lowermost position in full lines, and the position assumed by said cable when the skip approximately reaches the full line position shown in Fig. 1, at which time the reaches of the cable straighten out and converge toward the rear guide sheaves 18, 18'. The grooved sheaves 20, 20' hold the cable strands in proper spaced relation once they are brought into contact with the sheaves in the lowering movement of the skip and during the initial sector of pivotal swing of the skip when elevated. With this arrangement of the guide pulleys, it is clear that the skip may be raised to the required extent even with a low superstructure frame such as illustrated in the drawings, and it is no longer necessary under such conditions to provide a knock-down or pivotal superstructure such as referred to hereinbefore and commonly used today in apparatus of this type.

While the specific details of construction have been herein shown and described, the invention is not confined thereto as changes and alterations may be made without departing from the spirit thereof as defined by the appended claims.

Having thus described my invention, what I claim as new and desire to secure by Letters Patent is:

1. In concrete mixing apparatus of the class described, the combination of a supporting frame, a skip pivotally mounted on said frame and in its swing adapted to rise above the frame at its outer end, cable means for swinging the skip, spaced cable winding means therefor arranged within the frame in relatively closer relation than the width of the skip at the points of connection of the cable means therewith, cable sheaves mounted at the upper part of said frame substantially in the vertical planes over the cable winding means, guide sheaves mounted upon the end of the supporting frame spaced apart a greater distance than the cable sheaves aforesaid, the distance between said guide sheaves corresponding sub-

stantially to the distance between the sides of the skip at the points of connection of the cable means therewith, said guide sheaves being engaged by said cable means in its swing to loading position and adapted to hold the side reaches of the cable beyond the end of the frame substantially in the spaced relation corresponding to the connection points with the skip aforesaid when the skip is in its lowermost position.

2. In concrete mixing apparatus of the class described, the combination of a superstructure frame, a skip having diverging sides pivoted at its inner end within the sides of the frame and adapted in its swing to rise above said frame, cable means for swinging the skip having an operative connection with the sides of the skip remote from the narrow pivot end thereof, winding drums for said cable means mounted between the sides of the supporting frame in relatively closer relation than the width of the skip at the points of connection of the cable means therewith, guide sheaves mounted on the top and at the end of the frame and spaced apart a greater distance than said drums, said guide sheaves being arranged in such spaced relation as to maintain the side reaches of the cable spaced apart a greater distance than that represented by the width of that portion of the skip which passes within the plane of the frame sides during its swing.

3. In concrete mixing apparatus of the class described, the combination of a superstructure frame, a skip having diverging sides, said skip being pivotally connected at its inner end to said frame and in its swing adapted to rise above the frame at its outer end, a relatively short drum shaft mounted substantially centrally within the frame, a winding drum mounted on each end of said drum shaft, a pair of cables connected at their respective ends to said drums and at intermediate points with the sides of the skip remote from the pivot end, a pair of pulleys mounted over the winding drums over which the cables pass to dispose the reaches of the cable in vertical planes at the central portion of the frame, and a pair of relatively wide guide sheaves mounted upon the end of the frame and spaced apart a greater distance than the pulleys aforesaid, said guide sheaves being spaced a sufficient distance apart to maintain the side reaches of the cables extending from the previously mentioned pulleys out of the path of travel of the sides of the skip, said guide sheaves having grooved surfaces to hold the reaches of the respective cables spaced apart.

4. In concrete mixing apparatus of the class described, the combination of a supporting frame, a skip pivotally mounted on said frame and in its swing adapted to rise above the frame at its outer end, cable

means for swinging the skip, cable winding means therefor arranged within the frame, cable sheaves mounted on the frame above the winding means over which the side reaches of the cable extend, said cable sheaves being spaced apart a less distance than the distance between the points of connection of said side reaches with the skip, guide sheaves mounted upon the end of the supporting frame spaced apart a greater distance than the cable sheaves aforesaid, the distance between said guide sheaves corresponding substantially to the distance between the sides of the skip at the points of connection of the cable means therewith, said sheaves being engaged by said cable means in the swing of the skip to loading position and adapted to hold the side reaches of the cable beyond the end of the frame substantially in the spaced relation corresponding to the connection points with the skip aforesaid when the skip is in its lowermost position.

In testimony whereof I affix my signature.
